(57) **CLAIM**

The ornamental design for a handheld tickling device, as shown and described.

DESCRIPTION

FIG. 1 is a front, top perspective view of the handheld tickling device;

FIG. 2 is a right, side elevation view of the handheld tickling device, the left side being a mirror image thereof;

FIG. 3 is a front elevation view of the handheld tickling device;

FIG. 4 is a rear elevation view of the handheld tickling device;

FIG. 5 is a top plan view of the handheld tickling device; and,

FIG. 6 is a bottom plan view of the handheld tickling device. The broken lines shown in FIG. 6 are for the purpose of illustrating portions of the handheld tickling device that form no part of the claimed design.
